UNITED STATES PATENT OFFICE.

WALTER O. LUM, OF WILKINSBURG, PENNSYLVANIA, ASSIGNOR TO WESTINGHOUSE ELECTRIC AND MANUFACTURING COMPANY, A CORPORATION OF PENNSYLVANIA.

ELECTRICALLY-OPERATED SWITCH.

1,138,677.

Specification of Letters Patent. Patented May 11, 1915.

Application filed June 14, 1912. Serial No. 703,761.

To all whom it may concern:

Be it known that I, WALTER O. LUM, a citizen of the United States, and a resident of Wilkinsburg, in the county of Allegheny and State of Pennsylvania, have invented a new and useful Improvement in Electrically-Operated Switches, of which the following is a specification.

My invention relates to electromagnetically operated switches, and it has special reference to switches of this character which are adapted for use with systems of electric motor control.

One object of my invention is to provide a switch of the class above indicated that shall be simple and durable in construction and have the characteristics of operating only when the energy supplied to its actuating winding falls within predetermined limits.

Another object of my invention is to provide means for magnetically separating or insulating a pair of substantially parallel magnetic paths from each other that shall not constitute a short-circuited secondary winding for the flux in either path.

Independently operated switches are very largely used in the control of electric motors, and switches have been previously utilized for this purpose having two paths for the magnet flux, one of which predominates to hold the switch open when the energy supplied to the actuating coil exceeds a predetermined value, and the other of which predominates to close the switch when the current supplied to the coil falls within predetermined limits. In order to insure the lock-out action when a relatively large current is first supplied to the coil, the portion 30 of the magnetic circuit which is depended upon to close the switch has sometimes been provided with a short circuited coil or single turn of conducting material which tends to divert the flux into the other path.

According to my present invention, I utilize means for concentrating the leakage at a desired point in order to produce a maximum holding-out effect during the saturation of the branch of the core member which 45 is parallel to the leakage path. At the same time, I avoid short circuiting either path and, consequently, my invention is particularly well adapted for such switches as are called upon to operate on alternating cur-

rent circuits and are known as alternating current switches.

Figure 1 of the accompanying drawings is an elevation of an electrically operated switch constructed in accordance with my invention, Fig. 2 is a detail view of a damping coil of the switch shown in Fig. 1, and Fig. 3 is a view, corresponding to Fig. 2, of a modified structure which may be substituted for that of Fig. 2.

Referring to Figs. 1 and 2 of the drawings, the structure here shown comprises a slab or base 1 of insulating material, a stationary magnetizable member 2 secured thereto, a movable armature 3, a stationary switch contact member 4, a co-operating movable contact member 5, and an actuating coil 6. The stationary core member 2 is substantially U-shaped and is provided with a projection or lug 7 and a damper 8.

The movable armature 3 is provided with a projection 9 which forms an obtuse angle with the body of the armature and is provided with an adjusting screw 10. The armature is pivotally mounted on a pin 11 which is secured to a stationary bracket 12.

When the switch is open, the projection 9 of the armature is substantially parallel to an arm 13 of the stationary member 2 and the adjusting screw 10 engages the projection 7. The damper 8 is secured to the arm 13 adjacent to the projection 9 of the armature and forces the leakage flux, which traverses the projection 9, to pass through the projection 7. It is therefore evident that the leakage flux exerts a maximum force tending to hold the switch open.

The damper 8 is preferably made of copper or some good conducting material and formed as shown in Fig. 2. When so formed, it obviously tends to prevent the flux from passing through it. The damper may, however, constitute a plate of some good conducting material, as shown in Fig. 3, in which case the eddy currents set up in the plate will be depended upon to damp out the magnetic flux.

The operation of the switch is as follows: Assuming that the switch is open, if excessive current is supplied to the coil 6, a magnetic flux will be produced in the member 2 and, since the arm 13 is smaller in cross section, it will be saturated and the leakage flux which then traverses the projection 9

will prevent the switch from being closed. Substantially the same result will be secured if the arm 13 is so constructed or equipped that its magnetization will be effected slowly.

A reduction of the current through the coil 6 will reduce the magnetic flux, and the magnetic circuit will be completed through the branch 13 and the armature 3. Consequently, the armature will be tilted into the position shown in Fig. 1 and the switch will be closed.

When the switch is closed, the energy supplied to the coil 6 may be varied over comparatively wide limits without tending to open the switch, by reason of the fact that the projection 9 is then widely separated from the arm 13.

I desire that only such limitations shall be imposed as are indicated in the appended claims.

I claim as my invention:

1. A magnet comprising a U-shaped stationary magnetizable member, an armature pivotally mounted near the outer end of one branch of the U-shaped member and having a projection extending substantially parallel to said branch when the armature occupies one extreme position and at an angle to said branch when the armature occupies its other extreme position, and means for magnetically insulating the armature projection from the adjacent branch of the stationary member except at the free end of the projection.

2. A magnet comprising a U-shaped stationary magnetizable member, an armature pivotally mounted near the outer end of one branch of the U-shaped member and having a projection extending substantially parallel to said branch when the armature occupies one extreme position, and a damper of conducting material located at one side of the branch of the U-shaped member that is adjacent to the armature projection.

3. A magnet comprising a U-shaped stationary magnetizable member, an armature pivotally mounted near the outer end of one branch of the U-shaped member and having a projection extending substantially parallel to said branch when the armature occupies one extreme position, and a damper comprising a closed loop of conducting material interposed between the armature projection and the adjacent branch of the stationary magnetizable member and parallel to said branch.

4. An alternating current magnet switch comprising a stationary magnetizable member, a movable armature, a magnetizing coil,

the stationary member and the armature providing, when energized, two flux paths that tend to actuate the armature in opposite directions to respectively open and close the switch, and a damper comprising a closed turn of conducting material located in a plane between, and substantially parallel to, the two paths.

5. An alternating current magnet switch comprising a U-shaped stationary magnetizable member, a stationary contact member, an armature pivotally mounted near the outer end of one branch of the U-shaped member and having a projection extending substantially parallel to said branch when the switch is open, a movable contact member carried by the armature, the stationary magnetizable member and the armature providing two flux paths that tend, respectively, to open and close the switch, and means for magnetically insulating the two paths from each other.

6. An alternating current magnet switch comprising a U-shaped stationary magnetizable member, a stationary contact member, an armature pivotally mounted near the outer end of one branch of the U-shaped member and having a projection extending substantially parallel to said branch when the switch is open, a movable contact member carried by the armature, the stationary magnetizable member and the armature providing two flux paths that tend, respectively, to open and close the switch, and a damper of conducting material for magnetically insulating the two paths from each other.

7. An alternating current magnet switch comprising a U-shaped stationary magnetizable member, a stationary contact member, an armature pivotally mounted near the outer end of one branch of the U-shaped member and having a projection extending substantially parallel to said branch when the switch is open, a movable contact member carried by the armature, the stationary magnetizable member and the armature providing two flux paths that tend, respectively, to open and close the switch, and a damper comprising a closed turn of conducting material secured to the branch of the stationary magnetizable member adjacent to the armature projection.

In testimony whereof, I have hereunto subscribed my name this 27th day of May, 1912.

WALTER O. LUM.
